CLAIM

The ornamental design for a pair of shears, as shown and described.

DESCRIPTION

FIG. 1 is a front elevational view of a first embodiment of a pair of shears of the present invention;

FIG. 2 is a side view taken from the left side of the shears of FIG. 1;

FIG. 3 is a side view taken from the right side of the shears of FIG. 1;

FIG. 4 is a rear elevational view of the shears of FIG. 1;

FIG. 5 is an end view of the end of the handle of the shears of FIG. 1;

FIG. 6 is an end view of the blade end of the shears of FIG. 1;

FIG. 7 is a front elevational view of a second embodiment of a pair of shears of the present invention;

FIG. 8 is a side view taken from the left side of the shears of FIG. 7;

FIG. 9 is a side view taken from the right side of the shears of FIG. 7;

FIG. 10 is a rear elevational view of the shears of FIG. 7;

FIG. 11 is an end view of the handle end of the shears of FIG. 7;

FIG. 12 is an end view of the blade end of the shears of FIG. 7;

FIG. 13 is a front elevational view of a third embodiment of a pair of shears of the present invention;

FIG. 14 is a side view taken from the left side of the shears of FIG. 13;

FIG. 15 is a side view taken from the right side of the shears of FIG. 13;

FIG. 16 is a rear elevational view of the shears of FIG. 13;

FIG. 17 is an end view of the handle end of the shears of FIG. 13;

FIG. 18 is an end view of the blade end of the shears of FIG. 13;

FIG. 19 is a front elevational view of a fourth embodiment of a pair of shears of the present invention;

FIG. 20 is a side view taken from the left side of the shears of FIG. 19;

FIG. 21 is a side view taken from the right side of the shears of FIG. 19;

FIG. 22 is a rear elevational view of the shears of FIG. 19;

FIG. 23 is an end view of the handle end of the shears of FIG. 19; and,

FIG. 24 is an end view of the blade end of the shears of FIG. 19.
